ANKER PETERSEN, OF WINTHROP, MASSACHUSETTS, ASSIGNOR TO AMERICAN WIRE-MOLD COMPANY, OF HARTFORD, CONNECTICUT, A CORPORATION OF CONNECTICUT.

CARRIER DRIVE FOR BRAIDING MACHINES.

1,413,931.

Specification of Letters Patent. Patented Apr. 25, 1922.

Application filed July 30, 1920. Serial No. 400,170.

To all whom it may concern:

Be it known that I, ANKER PETERSEN, a citizen of the United States of America, and resident of Winthrop, in the county of Suffolk and State of Massachusetts, have invented new and useful Improvements in Carrier Drives for Braiding Machines, of which the following is a specification.

This invention relates to braiding machines and more particularly to that type in which a support having a series of thread carriers is mounted within a second support also provided with a series of thread carriers, the two series of carriers being revolved in opposite directions, movable guides being employed for carrying the strands of thread from said latter series of carriers over and under the carriers of the first series.

In machines of this type, the inner series of carriers must be so mounted and driven as to permit them to pass transversely across the strands from the outer carriers, and to this end such carriers may be propelled by means of driven rollers having frictional engagement with rotatable rolls mounted upon the carriers. One arrangement for accomplishing this result is disclosed in the patent to Peterson, 1,331,672, February 24, 1920. In the device of this patent the driving disc employed for imparting movement to the driving rolls must be accurately machined in order to secure proper driving engagement with the large number of rolls employed, and as this disc is necessarily thin and of large diameter, and as it is subjected to heavy stresses when rotated at the proper operative speed, it is found in practice that it frequently becomes distorted to such an extent as to fail to function in the desired manner.

One object of the present invention is to provide means for actuating the driving rolls of a character such that it may be readily and cheaply constructed, that it will simultaneously engage the entire series of rolls in proper manner, and will be of a character such that it will not readily be deformed in use.

In mechanisms of this type, it is very desirable that there shall be no slip between the driving rolls and the disc whereby they are actuated, as when such slip occurs the

movement of the carrier driven by said roll becomes uncertain, interfering with the proper laying of the strand at the braiding point.

A further object of the present invention is to so construct the driving roll as to avoid any slipping between the surface of the same and the actuating disc.

As a means for attaining the above objects, the circumferential portion of the driving disc may, if desired, be formed of a series of radially extending, resilient blades or plates which may be of spring steel or other suitable material; and as a roll actuating element, the ends of said blades may have secured thereto a continuous band or strip of suitable friction material connected to the several blades in any desired manner, as for example by means of rivets, a lacing cord or both. For cooperating with the strip carried by the actuating disc, the roll may be provided with a felt surface, and as herein disclosed, such felt surface may, if desired, take the form of a felt washer of substantial thickness, which may in itself constitute the driven element of the roll, being slipped upon an axle member and suitably secured thereto. One mode of carrying out the above objects is illustrated in the accompanying drawings, in which—

Figure 1 is a fragmentary, transverse, diametrical cross-section through a braiding machine of the type to which this invention is applied;

Figure 2 is a fragmentary top plan view of the roller actuating disc showing the leather strip connected thereto;

Figure 3 is a cross-section on the line *a—b* of Fig. 2; and

Figure 4 is a longitudinal cross-section through one of the driving rollers shown in Fig. 1.

Referring to the drawings, 1 is the frame of the machine, this frame being substantially spider-shaped and having a central hub 2 which supports a centrally-arranged tubular shaft 3 through which the braid is drawn, and at whose upper end is the braiding point. The shaft 3 is surrounded by sleeve 4 which is freely rotatable upon the shaft 3 and to which is keyed a bevel gear 5, such gear turning upon the upper face

of the hub 2. 7 is a driving shaft mounted in bearings carried in a bracket 8 secured to the frame, said shaft having secured at its inner end a pinion 10 which meshes with 5 and drives the gear 5.

11 is a revolving frame turning freely upon the shaft 4 above the gear 5, said frame carrying the usual strand guides in a manner common in the art and being provided 10 with a bevel gear 12 which also meshes with the pinion 10. By this arrangement of parts, it is evident that the frame 11, with the strand guides, will be rotated oppositely to the gear 5 and the sleeve 4.

15 Above the frame 11 a disc 13 is keyed to the sleeve 4 and turns therewith, and extending from the circumference of the disc 13 is a series of radial arms 16 upon which is mounted one (15) of a pair of concentric 20 rings, the other ring 14 being secured to the edge of the disc. The rings 14, 15, together with the disc 13 may be termed a roller-frame, and in each of the segmental spaces between the arms 16 and the rings 25 14, 15 is pivoted a roll 17.

The roll 17, as clearly illustrated in Fig. 4, comprises a tapered hub 18 provided at its extremities with axle members 19, 20, such axle members being constructed to turn 30 freely in suitable journal openings in the rings 14, 15 respectively. The hub 18 is preferably tapered from its outer end toward its inner end, and at its outer end is provided with a radial flange 21 provided 35 with a seat 22 upon which may be mounted a washer 23 of felt or similar non-abrasive material. For holding this washer in position, a thin metal washer 24 may be imposed thereon, and the several parts secured 40 in place by means of rivets 25 or other suitable devices. The washer 23, thus arranged, forms the driving element for propelling the braiding carriers.

26 is a heavy washer of felt, leather or like 45 material, providing a comparatively rough and resilient surface, such washer being slipped over the hub 18 and secured in position against the flange thereof by means of cement, or in any other suitable manner.

50 As will be noted, this washer is of substantial diameter as compared with that of the hub 18, and forms, in effect, a friction roll through which the drive roll may be actuated.

55 27 is a roller actuating disc keyed to the shaft 3, whereby it is prevented from rotating. The upper surface of this disc is inclined downwardly and outwardly, and to its peripheral portion are secured flat resilient plates 28, these plates being spaced apart and extending substantially radially. These plates will preferably be formed of spring steel, although other materials having the necessary qualities may be substituted therefor, if desired. To the under surface of the

plates 28, at their outer extremities, is connected a flat strip or band 29 of leather, felt or like frictional material, said band extending entirely around the series of plates and forming a continuous circle. This band 70 may be secured to the several plates of the series by means of rivets 30 or similar devices, and is also secured thereto by means of a lacing cord 31. This lacing cord passes across the intervals between the plates 28, 75 and in addition to securing the band 29 to the plates, acts to prevent any of the braiding strands from being whipped into the space between the plates 28, whereby they might be caught and broken. 80

32 illustrates a braiding carrier of usual form and such as is used in machines of this type, such braiding carrier being provided with a roll 33 adapted to engage with the driving roll 23, whereby the latter serves to 85 propel the carrier in performing its braiding function. The carrier 32 is also provided with a roller 34 which rests upon the upper surface of the disc 27, whereby the latter serves as a support for the inner ends 90 of the several carriers. In the usual manner, the carrier is provided with a roll 35 lying in a horizontal plane and engaging the groove 36 in the frame 11, whereby the carrier is supported against centrifugal action. 95

In the operation of the mechanism as herein described, the rolls 17 having been placed in position, the disc 27 is then secured to the shaft 3 with its leather band 29 resting upon the peripheral surfaces of the washers 26 of the several driving rolls. The carriers 32 are then placed in position, with their rolls 33 resting against the surfaces of the respective washers 23, and the machine is 100 otherwise assembled for use in the usual manner. Upon rotation of shaft 7, gear 5 is rotated, thereby rotating the disc 13, whereby the rolls 17 are bodily moved about the circumference of the frame 11. As the 110 rolls thus move bodily, the surfaces of the washers 26 engage the friction band 29 whereby they are caused to rotate, and through the engagement of the washers 23 with the carrier rolls 33, the latter are propelled through their circular path of travel, the strands passing freely between the rolls 33 and washers 23, as they are moved during the braiding operation. Due to the 115 resilient mounting of the contact member 29, it is unnecessary to machine the several parts with great accuracy, as the resilient plates readily yield to any inequalities in the diameters of the several rolls 26, such as may be occasioned by wear or accumulation of 120 lint thereon, or such as may occur through inaccuracy in the alinement of the central openings in the discs 27 and 13. This resilient mounting of the driving band thus insures proper driving engagement of the 125 130

same with the rolls 26 at all times and under all circumstances, whereby certainty of operation of driving rolls 17 is assured.

Furthermore, by the employment of felt 5 as a material for the rolls 26, all danger of slippage between said rolls and the driving element is eliminated, and by reason of the shape of the hub, wherein the tapering of the latter serves to securely wedge the roll in 10 position, it is easily understood that a roll 26 may be securely held in position when pressed firmly upon the hub, requiring the use of but little adhesive for securing it permanently. The employment of felt or similar soft resilient and non-abrasive material 15 as the drive element 23 whereby the carrier is propelled, serves to avoid any cutting or fraying of the yarn as it passes between the drive roll and the carrier roll, this being of 20 special importance when employing tender yarns.

Having thus described the invention in a preferred embodiment of the same, and the mode of operation thereof, what I claim and 25 desire to secure by Letters Patent of the United States is:

1. In a friction drive mechanism for braiding machines in combination, a hub, a friction element carried by said hub and 30 resilient means interposed between said hub and said friction element, said resilient means serving to support the friction element.

2. In combination in a friction drive 35 mechanism for braiding machines, a hub member, a series of resilient arms secured to said hub member, and a friction element secured to said arms and spaced from said hub.

3. In a friction drive for braiding machines in combination, a disc-like hub, a series of radially extending resilient fingers secured to said hub adjacent its periphery, and a friction band concentric with the axis 40 of said hub and secured to the free extremities of the respective fingers.

4. In combination in a drive mechanism of the class described, a disc member, a plurality of flat spring fingers secured to said 50 disc and projecting radially therefrom, and a circular friction element lying in a plane substantially parallel to that of the disc and supported by said fingers.

5. In a friction drive mechanism for 55 braiding machines in combination, a substantially circular support, a series of spring fingers spaced substantially equally about the periphery of said support, a band of friction material secured to the free extremities of the respective fingers and encircling said support, and lacing means for securing said band to said fingers.

6. In a friction drive for braiding machines in combination, a disc-like hub, a series 65 of flat, radially-extending arms secured

to said hub, a friction band lying in contact with one face of said arms, and a lacing element for securing said band to the respective arms, said lacing element bridging the space between the respective arms. 70

7. In a braiding machine having means for guiding a braiding strand, in combination, a braiding carrier and means for driving said braiding carrier, said means comprising a driving roll, a friction band for 75 driving the roll, a series of spaced resilient fingers for supporting said band, and means for bridging the space between said fingers to prevent the entrance therebetween of a braiding strand. 80

8. In combination in a braiding machine having means for guiding a braiding strand, in combination, a braiding carrier, means for supporting and guiding said carrier, and means for driving said carrier, such 85 means comprising a driving roll, means for bodily revolving said roll about the braiding axis, and a resiliently-supported friction-band for engaging an element of said roll, whereby to rotate the same about its 90 axis during its revolution.

9. In a braiding machine having a strand-guide, in combination, a braiding carrier, means for supporting and guiding said braiding carrier, and means for imparting a 95 movement of revolution to said carrier about the axis of the braiding machine, said means comprising a roll having an element constructed and arranged to engage an element of said carrier, means for imparting bodily 100 movement of revolution to said roll about the axis of the machine, a friction band for engaging an element of said roll, a plurality of resilient fingers having their outer extremities secured to said band, and a fixed 105 support for the inner ends of said fingers.

10. In combination in a braiding machine of the class described, a braiding carrier, means for supporting and guiding said carrier, whereby it is permitted to move in a 110 closed circular path, and means for imparting such movement to such carrier, said means comprising a roll having a drive-element and a driven element, a friction band engaging said driven element, resilient 115 means for supporting said band against circumferential movement, and means for moving said roll bodily in a circumferential direction.

11. In a braiding machine of the class described having a strand-guiding mechanism, in combination, a braiding carrier, means for supporting said braiding carrier whereby it is permitted to travel in a circular path, and means for imparting movement to 120 said carrier, said means comprising a roll having a driving element for engagement with said carrier and a driven element, means for imparting bodily movement of 125 revolution to said roll, a friction band con- 130

structed and arranged for contact with the peripheral surface of said driven element, a series of spaced, radially-extending, flat resilient arms for supporting said band, and 5 a fixed support upon which said arms are mounted.

12. In combination in a braiding machine of the class described, a carrier drive-roll comprising a hub member, a resilient washer mounted thereon and constituting a drive element, and a resilient washer secured upon said hub adjacent to said first washer and constituting a driven element. 10

13. In combination in a drive roll for braiding carriers, a tapered hub having a 15 radial flange at one extremity, a relatively thin washer of resilient material secured to said flange and constituting a carrier drive element, and a relatively thick washer of resilient material seated directly upon said hub adjacent to said flange and constituting a friction element whereby said roll may be turned. 20

Signed by me at Boston, Massachusetts, this 26th day of July, 1920.

ANKER PETERSEN.
